UNITED STATES PATENT OFFICE.

LEWIS CALVIN BULLOCK, JR., OF MILESBURG, PENNSYLVANIA.

CHAIR OR SWING SEAT.

No. 901,321.

Specification of Letters Patent.

Patented Oct. 20, 1908.

Application filed April 10, 1907. Serial No. 367,400.

To all whom it may concern:

Be it known that I, LEWIS CALVIN BULLOCK, Jr., a citizen of the United States of America, residing at Milesburg, in the county of Center and State of Pennsylvania, have invented new and useful Improvements in Chair or Swing Seats, of which the following is a specification.

This invention relates to chairs or swings, and the main object of the invention is to provide a chair or swing having a reversible back supported in a novel manner for ready adjustment, or, in other words, a back which may be easily shifted from one end of the seat to the other so as to enable the occupant to change his position and face in either of two opposite directions.

A further object of the invention is to provide novel means for securing and effectively bracing the reversible back of the seat equally well in either of its two positions.

Another object of the invention is to provide a novel frame construction embodying means for supporting the bottom of the seat and bracing the arms and arm rests relatively to the bottom frame.

With the above and other objects in view, the invention consists in the novel construction, combination and arrangement of parts, hereinafter more fully described, illustrated and claimed.

In the accompanying drawings, Figure 1 is a front elevation of a swing seat or chair embodying the present invention. Fig. 2 is a vertical cross-section through the same, on the line 2—2, of Fig. 1, showing the adjustment of the reversible back in full and dotted lines. Fig. 3 is an enlarged horizontal section, showing the manner of bracing and supporting the reversible back. Fig. 4 is a fragmentary bottom plan view, showing one of the bottom frame supporting corner plates.

The seat contemplated in this invention comprises essentially a bottom frame having end bars 1 and side bars 2, thereby forming a substantially rectangular frame of any desired size. Under the preferred embodiment of this invention, the side bars 2 are dished upon their upper sides, as shown in Fig. 2,

and the bottom of the seat is composed of parallel slats 4 extending over the side bars 2 and supported thereon and secured thereto in any usual or preferred manner.

Extending upward from the opposite sides 55 of the seat frame are arms, each of which is preferably composed of a bottom side bar 5, a top rail or arm rest proper 6, and interposed rungs or stanchions 7, the parts 5, 6 and 7 being firmly secured together. The 60 bottom side bars 5 lie just outside of and in contact with the side bars 2 of the bottom frame and are secured thereto and firmly clamped against the same by means of bolts 8 upon the inner ends of which are placed 65 thumb nuts 9 by the removal of which the arms of the chair or seat may be detached from the bottom.

The arms are provided at the ends with uprights 10 of considerable width to give 70 additional strength to the arms, and secured to the bottoms of the uprights 10 are corner plates 11 which extend back under the bars 5 and are also secured thereto as shown in the detail view, Fig. 4. The corner plates 75 11, carried thus rigidly by the arms, project under the seat frame 1, 2, and form supports for the bottom frame and thus sustain the weight of the bottom frame and the weight 80 of the occupant of the swing, while the bolts 8 serve to clamp the arms to the bottom frame. Extending upward through the arms and corner plates and through the top and bottom bars or rails of said arms and arranged at each corner of the seat, is an 85 eye bolt 12, the eye 13 at the upper end of which is adapted to receive one of the ropes of the swing, the said ropes not being shown.

Mounted between the arms of the chair or seat is a reversible back comprising a top 90 rail 14, a bottom rail 15 and interposed rungs or stanchions 16, said reversible back also comprising the rigidly attached side bars 17. Interposed between the reversible back and the arms are folding back supporting links or braces 18, two of said braces being shown and the same being pivotally connected at 19 to the center of the arm rest or top rail 6, as best shown in Fig. 2, while the outer end of each brace or link 18 is piv- 100

totally connected to the reversible back at the point 20 intermediate the top and bottom of the back, as clearly shown in the same figure. The side bars 17 of the reversible back are extended below the bottom rail 15 and provided with projecting tongues 21 adapted to enter between adjacent slats, as shown in Fig. 2, either at the back or front of the seat, the tongues 21, in connection with the braces 18, serving to sustain the reversible back of the seat or chair in a properly inclined position, as shown in full and dotted lines in Fig. 2.

When the back is in one or the other of its two positions of use, as shown in Fig. 2, the links or braces 18 lie in parallel line with and against the inner edges of the top rails or arm rests 6, by which means said links or braces and the back are prevented, in either one of the positions of use of the latter, from having lateral movement and straining the pivotal connections or parts of the swing. To reverse the back, or change the same from one side to the other of the seat, said back is lifted and, together with the braces 18, swung upward over the pivot points 19, and the parts are thus carried from one side of the seat to the other, the retaining tongues 21 being inserted between adjoining slats at the opposite side of the seat frame. The reversible back is of substantially the same form on both sides, and may be folded when not in use so as to lie flatwise upon the seat frame, as shown in dotted lines in Fig. 2, the links or braces 18 swinging downward to permit the back to be placed in such position.

It will be apparent that changes may be made in the form, proportion and minor details of construction without departing from the principle or sacrificing any of the advantages of the invention.

Having thus described the invention, what I claim is:

1. In a chair or swing seat, the combination of oppositely arranged arm rests having bottom rails and bottom frame supporting corner plates, a bottom frame mounted between the arms and having end bars in contact with the bottom rails of the arms, clamping bolts removably inserted through said end bars and bottom rails, and a back mounted between the arm rests.

2. A chair or swing seat comprising a bottom frame, arm rests at opposite ends thereof carrying supporting corner plates for the bottom frame, a back mounted between the arms, and eye bolts extending entirely through the arms from top to bottom thereof, said bolts also passing through said corner plates.

3. A reversible chair or swing seat comprising a seat frame provided with side bars having dished surfaces, slats secured to said bars and resting upon said surfaces, arms

at the sides of the seat frame having bottom bars detachably fastened to and arranged upon the outer sides of the side bars of the seat frame, a reversible back arranged between the arms, and links connecting the back with the arms, the lower edge of the back being provided with means to enter and interlock with the spaces between adjacent slats at the front and rear of the seat frame.

4. A chair or swing seat comprising a bottom having parallel slats, side bars for supporting said slats, said side bars being dished upon their upper edges, arm rests extending upward from the sides of the seat bottom, a reversible back comprising side bars and interposed rungs or stanchions, said side bars each having a tongue formed upon its lower end for insertion between the slats of the seat bottom, and pivotal links or braces connecting the reversible back with the arm rests.

5. A chair or swing seat comprising a bottom frame having side rails and end rails, arm rests provided with bottom rails secured to and arranged on the outer sides of said end rails and connected to uprights, corner plates fastened to the bottom rails and uprights and projecting beneath the end and side rails at the corners of the frame, and a back mounted between the arm rests.

6. A chair or swing seat comprising a bottom frame having side rails and end rails, arm rests provided with bottom rails arranged on the outer sides of said end rails and connected to uprights, fastenings detachably connecting the bottom rails to the end rails, corner plates fastened to the bottom rails and uprights and projecting beneath the end and side rails at the corners of the frame, eye-bolts passing through the uprights, and a back mounted between the arm rests.

7. A chair or swing seat comprising a main or seat frame having side rails, arms arranged at the sides of the frame, and each including a bottom rail, uprights rising therefrom, and an arm rest carried by the uprights, fastening means detachably securing the bottom rails of the arms to the side rails of the frame, reinforcing plates carried by the arms and extending under the side rails of the frame, and fastening means extending upwardly through the end uprights of each arm and fastening the plates to the bottom rails thereof, said means terminating at their upper ends in connections for the attachment of suspending ropes or the like.

8. A reversible chair or swing seat comprising a main frame, including side rails, arm rest frames independent of the main frame, and each including a bottom rail de-

tachably fastened to the adjacent side rail of the main frame, a reversible back, links connecting the arm rests of the arm frames with the reversible back, and supporting plates fixed to the bottom of each arm frame and projecting under the side rails of the main frame.

In testimony whereof, I affix my signature in presence of two witnesses.
